CLAIM

The ornamental design for a nursing garment substantially as shown and described.

DESCRIPTION

FIG. 1 is an isometric view of a first embodiment of a nursing garment in a first configuration.

FIG. 2 is an isometric view of the nursing garment of FIG. 1 in a second configuration and includes a component of a left shoulder portion in a raised position to show the environment underneath the component.

FIG. 3 is an isometric view of the nursing garment of FIG. 1 in a third configuration.

FIG. 4 is an isometric view of the nursing garment of FIG. 1 in a fourth configuration.

FIG. 5 is a front elevation view of the nursing garment of FIG. 1.

FIG. 6 is a rear elevation view of the nursing garment of FIG. 1.

FIG. 7 is a right side elevation view of the nursing garment of FIG. 1.

FIG. 8 is a left side elevation view of the nursing garment of FIG. 1.

FIG. 9 is a top plan view of the nursing garment of FIG. 1.

FIG. 10 is a bottom plan view of the nursing garment of FIG. 1.

FIG. 11 is an isolated zoomed-in view of the left shoulder portion of the nursing garment of FIG. 2.

FIG. 12 is an isometric view of the nursing garment of FIG. 1 in the first configuration with components of the left and right shoulder portions in raised positions to show the environment underneath the components.

FIG. 13 is an isometric view of a second embodiment of a nursing garment in a first configuration.

FIG. 14 is an isometric view of the nursing garment of FIG. 13 in a second configuration and includes a component of a left shoulder portion in a raised position to show the environment underneath the component.

FIG. 15 is an isometric view of the nursing garment of FIG. 13 in a third configuration.

(Continued)

FIG. 16 is an isometric view of the nursing garment of FIG. 13 in a fourth configuration.

FIG. 17 is a front elevation view of the nursing garment of FIG. 13.

FIG. 18 is a rear elevation view of the nursing garment of FIG. 13.

FIG. 19 is a right side elevation view of the nursing garment of FIG. 13.

FIG. 20 is a left side elevation view of the nursing garment of FIG. 13.

FIG. 21 is a top plan view of the nursing garment of FIG. 13.

FIG. 22 is a bottom plan view of the nursing garment of FIG. 13.

FIG. 23 is an isolated zoomed-in view of the left shoulder portion of the nursing garment of FIG. 14; and,

FIG. 24 is an isometric view of the nursing garment of FIG. 13 in the first configuration with components of the left and right shoulder portions in raised positions to show the environment underneath the components.

The broken lines in the drawings illustrate portions of the nursing garment that form no part of the claimed design. The dash double dot lines in FIGS. 2 and 14 are used to call out the features shown in FIGS. 11 and 23, respectively.

1 Claim, 20 Drawing Sheets
